UNITED STATES PATENT OFFICE

2,451,232

SWITCH CONTROL DEVICE

Claudius Russell McCauley, New Orleans, La.

Application June 29, 1945, Serial No. 602,308

6 Claims. (Cl. 200—53)

1

This invention relates to switch control devices such as would be suitable for use in conjunction with fuel, oil filling control systems for ships of the type disclosed in Patent No. 2,340,070, dated January 25, 1944, and which would also be suitable for use with valves employed in other systems.

The object of the invention is the provision of a switch operating arrangement wherein the switches are operated by and at the moment a valve is closed and are effectively locked in adjusted position against accidental or manual displacement in all other positions of the valve.

A further object is the provision of a switch operating control device embodying such features of structural simplicity as to permit its convenient application to conventional forms of screw operated valves whereby these may be utilized in the switch controlled part of such fluid systems as the one referred to in the patent above mentioned.

A still further object is to provide a switch operating mechanism that is of watertight construction such as required on board ship which will operate on the last quarter turn of the valve in its closing operation.

In the accompanying drawing wherein an approved embodiment of the invention is illustrated,

Fig. 1 is a top plan view of the switch control device constructed in accordance with the invention,

Fig. 2 is a side elevation thereof partly in section,

Fig. 3 is a detail sectional view through the switch casing,

Fig. 4 is a bottom plan view of the switch mechanism, the bottom of the casing being removed.

Referring to the drawing in detail, the numeral 10 designates generally a type of valve such as employed in the control device of Patent No. 2,340,070 for controlling the flow of fuel from the manifold to the fuel tanks. The valve is constituted by a usual casing provided with a bonnet 11 in which is threaded the screw stem 12 of the adjustable valve member, a hand wheel 13 being secured to the terminal of the screw stem by a nut 14.

In accordance with the invention an operating hood 15 is secured on the valve stem 12 under the hand wheel 13 by the nut 14 and participates in the combined rotary and axial movement of the stem incident to the opening and closing movements of the valve. The medial portion of the hood which is secured under the hand wheel 13 is dome shape and terminates in a skirt portion 16 depending from a flange 17. At a point immediately below the flange 17 the skirt 16 is formed with a slot 18 which is relatively narrow and of sufficient length to accommodate the switch actuating arm, as will be hereinafter more fully de-

2

scribed. As will be understood, the length of the slot 18 extends in the circumferential direction of the skirt 16 and the pin 19 is secured to the flange 17 by means of a threaded stem 20 passing through an aperture provided in a flange and cooperating with a nut 21. The pin 19 extends parallel with the valve stem 12 and the extent of the projection thereof beyond the flange 17 may be varied as required by turning the threaded stem 10 20 in the thread aperture in the flange 17 and subsequently securing the pin in adjusted position by tightening nut 21.

The switch controlled by the valve 10 was designated generally at 22 and the contact members 15 thereof are actuated by an arm 23 pivotally mounted at 24 and movable between fixed stops 25 integral with the casing of the switch. The arm 23, together with the pivot 24 thereof are those movable through an angle determined by the 20 space between the stops 25, and in moving from one position to the other the switch contacts are either opened or closed.

The supporting plate 26 having the switch casting is adjustably secured to the valve housing by 25 the bonnet bolts 27 in such position that in the two alternating positions of the arm 23 the latter is so disposed as to be held in an adjusted position by the depending skirt 16, except for the position of the valve in which the movable valve member 30 is substantially closed. In this position the skirt 16 occupies its lowermost position and in completing the last revolution of the hand wheel the pin 19 moves into the horizontal plane occupied by the arm 23 and, entering a terminal slot 28 therein, shifts the arm 23 from one position to the other. During the rocking movement of the arm 23 the terminal thereof passes through the slot 18 and is subsequently held against displacement by the skirt which thus constitutes a guard obstructing the movement of the switch arm.

The casing of the switch 22 is provided with a cover plate 29 formed with a depending support 30 in which the shaft 24 constituting the pivotal axis of the arm 23 is mounted. A retaining plate 45 31 having spaced notches 32 therein cooperates with a spring 33 whereby the switch arm and shaft are held in adjusted position against lost movement.

An operating cam 34 is secured to the shaft 24 50 and in one position thereof operates to depress the leaf springs 35 of the switches 37. Switches 37 are commercial type switches of the snap action type and totally enclosed in their own individual cases. These switches are bolted or otherwise secured to a supporting plate 38 attached to the cover plate 29 by a bolt 38a. Proper adjustment of the position of the switches 37 in relation to

the cam 34 is affected by adjusting screws 39 and 40 of which the screw 39 is threaded in the supporting plate 38 and is engageable with a stop member 41 on the cover plate 29 while the screw 40 is threaded in a block 42 integral with the cover 29 and is engageable with a shoulder 43 on the supporting plate 38.

The electrical connections to the switches 37 are made in the usual manner and for convenience in so doing a terminal block 44 provided with screw 45 are provided in the switch casing. The switch casing is also preferably of fluid tight construction and is provided with connections 46 for terminal tubes including the conductors extending to the switch contacts. Also, the casing is provided with a window 47 through which a lamp is visible for indicating to the operator the correct time for closing the valve.

As will be understood the switches 37 are to be used in conjunction with circuits such as employed in the electrically controlled fuel filling system of Patent No. 2,340,070. Further, the cooperation between the valve skirt 16, pin 19 and switch actuating arm 23 is such as to insure that the valve will be practically closed before the switches are operated and this is essential in the safe and efficient operation of control systems of the type to which the present invention refers. The pin 19 is so adjusted that during the last quarter of the valve stem 12 the terminal thereof moves into the horizontal plane of the actuating arm 23 and entering the slot 28 therein shifts the arm together with the shaft 24 from one position to the other. The rocking movement of the arm is accommodated by the slot 18 through which the arm projects during the movement from one position to the other. When the pin 19 passes out of the slot 28 incident to continued rotary movement of the valve, the skirt 16 engaging the arm 23 prevents unintentional displacement thereof and assures retention of the switch mechanism in its adjusted position. Incident to the opening movement of the valve, the hand wheel 13 is rotated in the reverse direction, and in so doing the pin 19 re-enters the slot 28 thereby rocking the arm 23 into the first position. The skirt 16 is of sufficient length in the direction of the axis of the screw stem 12 to enable the valve to be completely open and at the same time maintain cooperative relation between said skirt and the arm 23.

What I claim is:

1. In combination, a rotatable and axially displaceable valve operating screw, a switch operating lever, means movable axially and rotatably with said screw to engage and operate the switch operating lever when the screw has reached a predetermined axial position, and stop means for said switch operating lever movable with said screw effective in all other positions of said screw for preventing operation of said switch operating lever.

2. In combination, a rotatable and axially displaceable valve operating screw, a switch operating lever, means movable rotatably and axially with said screw to engage and operate the switch operating lever when the screw has reached a predetermined position in its axial travel, and a skirt shaped means carried by said screw and movable therewith to obstruct the movement of the switch operating lever in all other axial positions of the screw.

3. In combination, a rotatable and axially displaceable valve operating screw, a switch operating lever movable in a plane at right angles to

said screw, abutment means for limiting arcuate movement of the switch operating lever, means carried by said screw and operable in a predetermined axial position of said screw for engaging and moving said lever through its arcuate limits of movement, and means carried by said screw and effective in all other positions of said screw to obstruct movement of said switch operating lever.

10. 4. In combination a rotatable and axially displaceable valve operating screw, a switch operating lever movable between fixed arcuate limits mounted adjacent said screw, a flange having an adjustable pin near its periphery carried by said screw and engageable with said switch operating lever at a predetermined axial position of said screw for moving said switch operating lever between said fixed arcuate limits and a skirt means carried by said valve operating screw effective through all other positions of said valve operating screw for maintaining said switch operating lever at the limits of its arcuate movement.

5. In combination a rotatable and axially displaceable valve operating screw, a switch operating lever swingably mounted adjacent said screw, a flange carried by said screw and movable therewith in an axial direction and rotatable therewith, a pin adjustable mounted near the periphery of said flange and engageable with said switch operating lever in a predetermined position of said valve operating screw to operate said switch operating lever, and a skirt means also carried by said valve operating screw and movable therewith adjacent the end of said lever for preventing movement of said lever in all other positions of said valve operating screw, said skirt including a slot adjacent the pin on said flange permitting the free movement of said lever when engaged by said pin.

30. 6. In combination, a rotatable and axially displaceable valve operating screw, a switch operating shaft mounted parallel and adjacent to said screw, a lever on one end of said shaft extending toward said screw and movable between fixed limits; a flange carried by said screw and rotatable and axially movable therewith, a pin screw threaded through said flange and engageable with said lever in predetermined axial positions of said 35. valve operating screw for moving said lever from one to the other of its limits of movements, a skirt means carried by said valve operating screw and movable rotatably and axially therewith and provided with a slot adjacent the pin and effective through all other axial positions of the valve operating screw for maintaining the switch operating lever at the limits of its movement.

CLAUDIUS RUSSELL McCUALEY.
